CAN LIFTING AND CARRYING DEVICE

Robert M. Weir, Salem, Oreg.

Application December 17, 1943, Serial No. 514,697

4 Claims. (Cl. 294—87)

This invention relates to an improved device particularly adapted for use in simultaneously lifting and carrying two ice cream cans from one place to another.

The primary object of the present invention is to provide a simple, durable and highly efficient device of the above kind.

A further object of the present invention is to provide a can lifting and carrying device of the above kind which is easy to use and manipulate, and otherwise well adapted to meet the requirements for a successful commercial use.

The present invention consists in the novel form, combination and arrangement of parts hereinafter more fully described, shown in the accompanying drawings and claimed.

In the drawings, wherein like reference characters indicate corresponding parts throughout the several views:

Figure 1 is an elevational view showing a lifting and carrying device constructed in accordance with the present invention and operatively engaged with two ice cream cans.

Figure 2 is an end elevational view of the device shown in Figure 1, with the cans omitted.

Figure 3 is a view somewhat similar to Figure 1, drawn on a larger scale, and with parts broken away and in section to more clearly reveal details of construction, the cans being omitted.

Figure 4 is a top plan view of the device shown in Figure 2, and

Figure 5 is a vertical section taken on line 5—5 of Figure 3.

Referring in detail to the drawings, the present can lifter and carrier comprises a horizontal elongated rigid supporting bar 5 having a rigid arm 6 depending from the intermediate portion thereof, oppositely and outwardly facing arcuate can-engaging jaws 7 and 8 being carried by the lower end of the arm 6. Bell crank levers 9 and 10 are pivoted at 9a and 10a to opposite ends of the supporting bar 5 for swinging movement in a vertical plane, and these levers have arms 9b and 10b depending below the supporting bar 5 and provided upon their lower ends with oppositely and inwardly facing arcuate can-engaging jaws 11 and 12. The other arms 9c and 10c of the bell crank levers extend inwardly toward each other directly above the supporting bar 5 and have their adjacent inner ends connected by a flexible member 13 consisting of a rubber tube or the like snugly and slidably fitted over the adjacent ends of said lever arms 9c and 10c. Helical compression springs 14 and 15 are seated in cup-shaped members 16 and 17 fixed

upon the supporting bar 5, and the upper ends of these springs are connected to the lever arms 9c and 10c, as at 18 and 19. The arrangement is such that the springs 14 and 15 act to normally elevate the lever arms 9c and 10c so as to swing the lever arms 9b and 10b inwardly toward each other.

In using the present device, the lever arms 9c and 10c are formed toward the supporting bar 5 by manual pressure against the action of springs 14 and 15. The arm 6 is disposed between a pair of adjacent ice cream cans C and C' so that the jaws 7 and 8 respectively engage the adjacent side of the can C and the adjacent side of the can C'. The lever arms 9c and 10c are then released so that the springs 14 and 15 swing the levers 9 and 10 to bring the arms 9b and 10b inwardly and thereby cause gripping engagement of the jaws 11 and 12 with the other sides of the respective cans, with the jaws 7 and 8 and the jaws 11 and 12 disposed beneath the marginal rims 20 and 21 at the tops of the cans. Upon gripping and pulling upwardly upon the flexible connecting member 13 the bell crank levers will be forced and maintained in position to tightly grip the cans so that they may be conveniently lifted and carried from one place to another. Should it be necessary to set the cans down one or more times before arriving at the desired destination for the cans, the lifting and carrying device will remain in operative engagement with the cans due to the action of the springs 14 and 15. However, when it is desired to disengage the device from the cans, the member 13 is forced toward the bar 5 so as to swing the levers 9 and 10 in a direction to cause outward movement of the arms 9b and 10b and disengagement of the jaws 11 and 12 from the outer sides of the cans.

The pivotal connections of levers 9 and 10 with the supporting bar 5 are preferably effected by forking the ends of said bar 5 to receive the levers and to provide ears through which the pins of the pivots extend. It will be seen that I have provided a very simple and durable, as well as highly efficient can-lifting and carrying device of the kind described. The device is easy to use and manipulate and will remain in engagement with the cans until intentionally disengaged therefrom. Minor changes in the details of construction illustrated and described are contemplated within the spirit and scope of the invention as claimed.

What I claim as new is:

1. A device for simultaneously lifting and carrying two cans, comprising an elongated rigid

supporting bar, an arm rigid with and depending from the intermediate portion of said supporting bar, oppositely and outwardly facing arcuate can-engaging jaws carried by the lower end of said arm, bell crank levers having arms pivoted to opposite ends of the supporting bar and depending below the latter, further oppositely and inwardly facing arcuate can-engaging jaws on the lower ends of said arms, said levers having other arms extending inwardly toward each other above the supporting bar, and a flexible connection between the inner ends of said last-named arms.

2. A device for simultaneously lifting and carrying two cans, comprising an elongated rigid supporting bar, an arm rigid with and depending from the intermediate portion of said supporting bar, oppositely and outwardly facing arcuate can-engaging jaws carried by the lower end of said arm, bell crank levers having arms pivoted to opposite ends of the supporting bar and depending below the latter, further oppositely and inwardly facing arcuate can-engaging jaws on the lower ends of said arms, said levers having other arms extending inwardly toward each other above the supporting bar, and a flexible connection between the inner ends of said last-named arms, said last-named connection comprising a flexible tubular member slidably telescoped onto the adjacent ends of said arms.

3. A device for simultaneously lifting and carrying two cans, comprising an elongated rigid supporting bar, an arm rigid with and depending from the intermediate portion of said supporting bar, oppositely and outwardly facing arcuate can-engaging jaws carried by the lower

end of said arm, bell crank levers having arms pivoted to opposite ends of the supporting bar and depending below the latter, further oppositely and inwardly facing arcuate can-engaging jaws on the lower ends of said arms, said levers having other arms extending inwardly toward each other above the supporting bar, and a flexible connection between the inner ends of said last-named arms, and helical compression springs interposed between the last-named arms of the levers and said supporting bar for normally yieldingly maintaining the jaws in gripping engagement with the cans.

4. A device for simultaneously lifting and carrying two cans, comprising an elongated rigid supporting bar, an arm rigid with and depending from the intermediate portion of said supporting bar, oppositely and outwardly facing arcuate can-engaging jaws carried by the lower end of said arm, bell crank levers having arms pivoted to opposite ends of the supporting bar and depending below the latter, further oppositely and inwardly facing arcuate can-engaging jaws on the lower ends of said arms, said levers having other arms extending inwardly toward each other above the supporting bar, and a flexible connection between the inner ends of said last-named arms, and helical compression springs interposed between the last-named arms of the levers and said supporting bar for normally yieldingly maintaining the jaws in gripping engagement with the cans, the upper ends of said springs being connected with the lever arms, and cup members on the supporting bar in which the lower ends of said springs are seated.

ROBERT M. WEIR.
